UNITED STATES PATENT OFFICE.

EVERETT S. CAMERON, OF BEVERLY, MASSACHUSETTS

VALVE-ACTION FOR EXPLOSIVE-ENGINES.

981,165.

Specification of Letters Patent. Patented Jan. 10, 1911.

Application filed March 21, 1910. Serial No. 550,704.

To all whom it may concern:

Be it known that I, EVERETT S. CAMERON, a citizen of the United States, residing at Beverly, in the county of Essex and State of Massachusetts, have invented certain new and useful Improvements in Valve-Actions for Explosive-Engines, of which the following is a specification.

My invention relates to an improved means designed to automatically open the intake-valve and exhaust-valve of explosive engines, and the invention consists of a cam-actuated rock-shaft mounted at each side and centrally of a pair of engine-cylinders, each shaft having an integral U-shaped portion or fork whose ends come alternately in contact with the stems of the intake-valves or exhaust-valves.

The object of my invention is to lessen the number of rock-shafts or levers as ordinarily employed to open the intake and exhaust valves, and at the same time render convenient of access to lubricate the moving parts within the crank-case.

To this end my invention consists of the novel construction, arrangement, and combination of parts, as hereinafter described and claimed.

In the accompanying sheet of drawings, Figure 1 represents an explosive engine, partly in elevation and partly in section, taken on line 1.—1. of Fig. 2, showing the parts embodying my improvement. Fig. 2 is a central vertical section, taken on line 2.—2. of Fig. 1, and; Fig. 3 is a plan view as seen on line 3.—3. of Fig. 1.

Like reference characters indicate like parts.

My improved structure of valve action is designed for use in connection with that class of reciprocating type of explosive engines in which expanding springs are employed to close the intake valve and exhaust valve.

In the drawings I represent my improvement as applied to an ordinary vertical two-cylinder explosive engine, wherein the intake-valve *i* and exhaust-valve *j* are disk-shaped and each valve having its stem *k* projecting transversely over each engine-cylinder *l*, each stem surrounded by an expanding coil spring *m* to close each valve upon its seat, and the crank-shaft *n* journaled in bonnets *o*, *o* which close the ends of the crank-case *p*.

My improvement is as follows: On each

side and centrally of a pair of engine-cylinders *l*, *l* is an upwardly extending tubular member or support *a* having a screw-threaded portion *a*¹ to engage a threaded opening 60 formed through the wall of the crank-case *p*, and each support has a hexagonal head *a*² to receive a wrench in securing said support firmly in position.

A shaft *b* passes loosely through each support *a* and each shaft has a U-shaped member or fork *b*¹ fast on one end thereof, and the free ends of each fork *b*¹ are each provided with a screw-threaded opening therethrough to receive a screw *c* for contacting with the end of each valve-stem *k*. The other end of each shaft *b* is journaled in a hub formed integral and within the crank-case, as at points *b*², *b*² in Fig. 2, and above each hub the shafts *b*, *b* have each a downwardly extending arm *b*³ to rest upon oppositely-disposed working-faces of a pair of disk members *d*, *d*, which are fast on a shaft *e*. A collar *f* is secured on each shaft *b* to prevent a sliding movement of the latter on 75 each support *a*.

A rotary motion is imparted to the cam-shaft *e* by means of a small spur gear *g* fast on the crank-shaft *n* and in mesh with a large spur gear *g*¹ fast on said shaft *e*. The 85 cam-shaft *e* is designed to have endwise movement within the crank-case *p*, by means of screws *h*, *h* which engage threaded openings formed through the bonnets *o*, *o*, and each screw has a conical point *h*¹ to fit a corresponding size of conical opening formed at each end of said shaft *e*, and each screw *h* is provided with a slot *h*² for the insertion of the point of a screw-driver to bring the raised working-faces which act as cams *d*¹, 95 *d*¹ to their proper degree of adjustment to actuate the forked-shafts *b*, *b*. The ends of the shaft-arms *b*³, *b*³ rest upon the shaft *e*, and between the cams of the fixed disk-members *d*, *d*. The screws *c*, *c* permit of regulating the proper amount of opening to be given the intake and exhaust valves. A check-nut *h*³ is mounted on each screw *h* (Fig. 1.) to impinge against the face of each bonnet *o* in holding each screw firmly in 100 place. The cams *d*¹, *d*¹ are positioned diagonally opposite each other and are so timed that as one cam acts to swing one shaft-arm *b*³ in one direction the cam next following acts to swing the opposite shaft-arm *b*³ in the 105 reverse direction, and so on throughout the revolution of the disk-members *d*, *d*, and

110

whereby a vibratory motion is imparted to the shafts b , b to alternately open both intake-valves of one pair of engine-cylinders and also open both exhaust-valves of said cylinders, in the manner shown in Figs. 2 5 and 3. Therefore, it is seen that by use of my improvement I provide a structure of valve action that is simple; its working parts readily adjusted; having ample room to lubricate its working parts, and at the same time a structure that lessens the cost in the manufacture of this class of engine.

Having described my improvement, what I claim and desire to secure by Letters-Pat- 10 ent, is—

1. In an explosive engine having one or more pair of piston cylinders each provided with a spring controlled intake stem-valve and a spring controlled exhaust stem-valve, 15 and a crank case communicating with the cylinders, a fixed tubular support at each side of and between each pair of cylinders, a vertically-disposed rock shaft extending through each support and journaled at its lower end in the crank case, each of said rock shafts having a U-shaped member at its 20 upper end and an integral inwardly-extending arm at a point removed from its inner end, a driven shaft disposed at right angles with respect to said rock shaft, and a pair of spaced disks secured to the driven shaft and having cam faces contacting with said arms for actuating the rock shaft whereby the ends of said U-shaped members are moved 25 against the valve stem for opening either the intake or exhaust valve against the action of their springs.

2. In an explosive engine having one or more pair of piston cylinders each provided 30 with a spring controlled intake stem-valve and a spring controlled exhaust stem-valve, and a crank case communicating with the cylinders, a fixed tubular support at each side of and between each pair of cylinders, a vertically-disposed rock shaft extending through 35 each support and journaled at its lower end in the crank case, each of said rock shafts having a U-shaped member at its upper end and an integral inwardly-extending arm at 40 a point removed from its inner end, a driven shaft disposed at right angles with respect to said rock shaft, a pair of spaced disks secured to the driven shaft and having cam faces contacting with said arms for actuating the rock shaft whereby the ends of said U-shaped members are moved 45 against the valve stem for opening either the intake or exhaust valve against the action of their springs, and means to permit of lateral adjustment of the driven shaft.

3. In an explosive engine having one or more pair of piston cylinders each provided with a spring controlled intake stem-valve and a spring controlled exhaust stem-valve, 50 and a crank case communicating with the

cylinders, a fixed tubular support at each side of and between each pair of cylinders, a vertically-disposed rock shaft extending through each support and journaled at its lower end in the crank case, each of said rock shafts having a U-shaped member at its upper end and an integral inwardly-extending arm at a point removed from its inner end, a driven shaft disposed at right angles with respect to said rock shaft, a pair of spaced disks secured to the driven shaft and having cam faces contacting with said arms for actuating the rock shaft whereby the ends of said U-shaped members are moved 55 against the valve stem for opening either the intake or exhaust valve against the action of their springs, and means to permit of lateral adjustment of the driven shaft, and means for rotating the driven shaft.

4. In an explosive engine, the combination of a pair of piston cylinders each provided with a spring controlled intake stem-valve and a spring controlled exhaust stem-valve normally maintained in closed position by their springs, a driven shaft, a pair of cam disks fixed to said shaft, a pair of upright rock shafts arranged at the side of and between each pair of cylinders, each of said rock shafts having a forked upper end 60 and an integral arm at its lower end engaging with said cam disk whereby said shafts are operated, and a screw mounted in each of the arms of the forked end of each shaft and abutting against the valve stem 65 whereby the intake and exhaust valves are alternately opened when the rock shafts are operated.

5. In an explosive engine, the combination of a pair of piston cylinders each provided with a spring controlled intake stem-valve and a spring controlled exhaust stem-valve normally maintained in closed position by their springs, a driven shaft, a pair of cam disks fixed to said shaft, a pair of upright rock shafts arranged at the side of and between each pair of cylinders, each of said rock shafts having a forked upper end and an integral arm at its lower end engaging with said cam disk whereby said rock shafts are operated, a screw mounted in each of the arms of the forked end of each shaft and abutting against the valve stem whereby the intake and exhaust valves are alternately opened when the rock shafts are operated, 110 and means to permit of lateral adjustment of the driven shaft.

6. In an explosive engine, the combination with a pair of piston cylinders each provided with a spring controlled intake stem-valve and a spring-controlled exhaust stem valve, said valve normally maintained in closed position by the action of said springs, a crank casing communicating with said cylinders, of a pair of upright rock 115

shafts journaled at their lower ends in the crank case, a fork carried upon the upper ends of each of the rock shafts and engaging with the valve stems for shifting the valves to open position when the rock shafts are actuated, inwardly-extending arms projecting from the lower portions of said shafts, a driven shaft, a pair of spaced cam disks fixed to the driven shaft and adapted to engage said arms whereby the rock shafts are actuated for alternately opening and closing the intake valves against the action of their springs.

7. In an explosive engine, the combination with a pair of piston cylinders each provided with a spring controlled intake stem-valve and a spring controlled exhaust stem-valve, said valve normally maintained in closed position by the action of said springs, a crank casing communicating with said cylinders, of a pair of upright rock shafts journaled at their lower ends in the crank case, a fork carried upon the upper ends of each of the rock shafts and engaging with the valve stems for shifting the valves to open position when the rock shafts are actuated, inwardly-extending arms projecting from the lower portions of said shafts, a driven shaft, a pair of spaced cam disks fixed to the driven shaft and adapted to engage said arms whereby the rock shafts are actuated for alternately opening and closing the intake valve against the action of their springs, and adjustable means carried by the forks for controlling the opening movement of the valves.

8. In an explosive engine the combination with a pair of piston cylinders each provided with a spring controlled intake stem-valve and a spring controlled exhaust stem-valve; said valve normally maintained in closed position by the action of said springs, a crank casing communicating with said cylinders, of a pair of upright rock shafts journaled at their lower ends in the crank case, a fork carried upon the upper ends of each of the rock shafts and engaging with the valve stems for shifting the valves to open position when the rock shafts are actuated, inwardly-extending arms projecting from the lower portions of said shafts, a driven shaft, a pair of spaced cam disks fixed to the driven shaft and adapted to engage said arms whereby the rock shafts are actuated for alternately opening and closing the intake valves against the action of their springs, and means for alternately adjusting said driven shaft for positioning the cam disks in operative relation with respect to said arm.

9. In an explosive engine, the combination with a pair of piston cylinders each provided with a spring controlled intake stem-valve and a spring controlled exhaust stem-valve, said valve normally maintained

in closed position by the action of said springs, a crank casing communicating with said cylinders, of a pair of upright rock shafts journaled at their lower ends in the crank case, a fork carried upon the upper ends of each of the rock shafts and engaging with the valve stems for shifting the valves to open position when the rock shafts are actuated, inwardly-extending arms projecting from the lower portions of said shafts, a driven shaft, a pair of spaced cam disks fixed to the driven shaft and adapted to engage said arms whereby the rock shafts are actuated for alternately opening and closing the intake valve against the action of their springs, adjustable means carried by the forks for controlling the opening movement of the valves, and means for alternately adjusting said driven shaft for positioning the cam disks in operative relation with respect to said arm.

10. In an explosive engine, the combination with a pair of piston cylinders each provided with a spring controlled intake stem-valve and a spring controlled exhaust stem-valve, said valves normally maintained in closed position by their springs, and means to constitute a crank case communicating with said cylinders, of a pair of upwardly-extending tubular supports fixed to said means and projecting outwardly at an inclination with respect to each other, said supports arranged between the pair of cylinders, a rock shaft extending through each of the supports and journaled at its lower end in said means, a fork carried upon the upper end of each of the rock shafts and adapted to engage the valve stems of each cylinder for longitudinally shifting them when the rock shaft is actuated whereby the plates are alternately open against the action of their springs, inwardly-extending arms projecting from said rock shaft at the lower end thereof, a driven shaft supported by said means and disposed substantially at right angles with respect to the rock shaft, and a pair of disks secured to the driven shaft and each provided with cam faces contacting with said arms for actuating each of the rock shafts alternately in opposite directions.

11. In an explosive engine, the combination with a pair of piston cylinders each provided with a spring controlled intake stem-valve and a spring controlled exhaust stem-valve, said valves normally maintained in closed position by their springs, and means to constitute a crank case communicating with said cylinders, of a pair of upwardly-extending tubular supports fixed to said means and projecting outwardly at an inclination with respect to each other, said supports arranged between the pair of cylinders, a rock shaft extending through each of the supports and journaled at its lower

end in said means, a fork carried upon the upper end of each of the rock shafts and adapted to engage the valve stems of each cylinder for longitudinally shifting them 5 when the rock shaft is actuated whereby the plates are alternately open against the action of their springs, inwardly-extending arms projecting from said rock shaft at the lower end thereof, a driven shaft supported 10 by said means and disposed substantially at right angles with respect to the rock shaft, a pair of disks secured to the driven shaft and each provided with cam faces contacting with said arms for actuating each of the 15 rock shafts alternately in opposite directions, and means carried by the forks for controlling the opening movement of the valves.

12. In an explosive engine, the combination 20 with a pair of piston cylinders each provided with a spring controlled intake stem-valve and a spring controlled exhaust stem-valve, said valves normally maintained in closed position by their springs, and 25 means to constitute a crank case communicating with said cylinders, of a pair of upwardly-extending tubular supports fixed to said means and projecting outwardly at an inclination with respect to each other, said 30 supports arranged between the pair of cyl-

inders, a rock shaft extending through each of the supports and journaled at its lower end in said means, a fork carried upon the upper end of each of the rock shafts and adapted to engage the valve stems of each 35 cylinder for longitudinally shifting them when the rock shaft is actuated whereby the plates are alternately open against the action of their springs, inwardly-extending arms projecting from said rock shaft at the lower 40 end thereof, a driven shaft supported by said means and disposed substantially at right angles with respect to the rock shaft, a pair of disks secured to the driven shaft and each provided with cam faces contacting with said arms for actuating each of the rock shafts alternately in opposite directions, means carried by the forks for controlling the opening movement of the valves, and means for alternately adjusting 45 said driven shaft for positioning the disks in operative relation with respect to said arms.

In testimony whereof I affix my signature in presence of two witnesses.

EVERETT S. CAMERON.
